TRAY

Lorraine Farkas, New York, N. Y.

Application January 6, 1944, Serial No. 517,213

3 Claims. (Cl. 65—53)

This invention relates to new and useful improvements in a tray.

More specifically, the invention proposes the construction of a tray arranged in a manner to permit its carrying capacity to be increased by the extension of tray end members from a central member in a manner to increase the size of the tray to permit a greater number of articles to be placed thereon.

Still further it is proposed to characterize the central member by a base wall and a pair of side walls extending upwards from the base wall and which have the tray end members slidably mounted thereon between the side walls and which are provided with a means for connecting the tray end members to the upwardly extending side walls in a manner to limit the extension of the tray end members.

Still another object of the invention proposes mounting a tray extension plate vertically slidably upon the base portion of the central member and which is adapted to move upwards between the adjacent ends of the tray end members when they are extended in a manner to form a tray which will have a flat surface when extended.

A further object of the invention proposes the provision of a resilient means upon the central member for urging the tray extension plate into a raised position between the adjacent ends of the tray end members in their completely extended position in a manner to retain the tray extension plate in position and to prevent the tray end members from moving inwards when articles are in position upon the tray.

Still another object of the invention proposes the provision of handles mounted upon the tray end members and which are connected with the tray extension plate in a manner so that the handles may be pivoted, urging the tray extension plate downwards so that the tray end members may be moved into a collapsed position relative to the central member.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of the tray constructed in accordance with this invention.

Fig. 2 is a view similar to Fig. 1 but illustrating the tray end members extended.

Fig. 3 is an enlarged vertical sectional view taken on the line 3—3 of Fig. 1.

Fig. 4 is an enlarged vertical sectional view taken on the line 4—4 of Fig. 2.

Fig. 5 is an enlarged partial vertical sectional view taken on the line 5—5 of Fig. 4.

Fig. 6 is a plan view of a tray constructed in accordance with a modification of this invention.

Fig. 7 is a longitudinal vertical sectional view taken on the line 7—7 of Fig. 6.

The tray according to this invention, includes a central member 10 which has a base wall 11 and upwardly extending side walls 12 which continue from the base wall 11.

15 Tray end members 13 are slidably mounted upon the base wall 11 and between the side walls 12. Each of the tray end members 13 is alike in construction and each is provided at its outer end with an integrally formed handle 14.

20 Means is provided between the tray end members 13 and the upwardly extending side walls 12 of the central member 10 for limiting the extension of the end tray members 13 with relation to the central member 10. This means comprises

25 pins 15 mounted upon the end tray members 13 and which engage into elongated slots 16 formed in the inside faces of the upwardly extending side walls 12 of the central member 10. Extension of the end tray members 13 relative to the central member 10 may be continued until the pins 15 strike the ends of the slots 16.

30 A tray extending plate 17 is vertically slidably mounted upon the base portion 11 of the central member 10. The tray extension plate 17 is provided for the purpose of moving vertically upwards between the inner edges of the tray end members 13 when they are completely extended relative to the central member 10. Leaf springs 18 have one of their ends attached to the base

35 wall 11 by means of pins 19. The free ends of the leaf springs 18 extend upwards and engage the bottom face of the tray extension plate 17. The leaf springs 18 comprise resilient means for urging the tray extending plate 17 into its raised position.

40 The side walls 12 of the central member 10 are formed with shoulders 20 against which the edges of the tray extension plate 17 are adapted to strike to limit the upward movement of the tray extension plate 17 to a position in which its top face will be flush with the top faces of the tray end members 13.

45 The manner of using the tray is as follows:

Normally the tray will be collapsed in a position similar to that shown in Figs. 1 and 3 with

the tray extension plate 17 in an inoperative position beneath the tray end members 13. If it is found that the carrying capacity of the tray is too small for the particular job at hand, the tray end members 13 may be pulled into a completely extended position relative to the central member 10 and until the pins 15 strike the ends of the slots 16. In a completely extended position of the end tray members 13, the leaf springs 18 will immediately urge the tray extension plate 17 into a raised position between the adjacent ends of the tray end members 13. This will materially increase the carrying capacity of the tray as shown in Figs. 2 and 4.

To again collapse the tray, it is merely necessary to rest it upon a solid surface and press downwards upon the tray extension plate 17 while urging the tray end members 13 laterally inwards into a collapsed position relative to the central member 10. It will be noted that the tray extension plate 17 in addition to providing the flush surface on the tray when extended, serves to maintain the tray end members against moving inwards while articles are in position upon the tray.

In the form of the invention shown in Figs. 6 and 7, it will be noted that the tray extension plate 17 is formed of support sections 17', one for each tray end member 13. The provision of the support tray extension plates 17' permits either one or the other of the end tray members 13' to be extended independently of the other permitting its respective tray extension plates 17' to move into a raised position to provide a flush surface upon the tray.

Means is also provided in this form of the invention for automatically moving the tray extension plates 17' into a depressed condition when it is desired to move the tray end members 13 into their collapsed position. In this form of the invention, the handles 14' provided upon the tray end members 13 are pivotally supported by means of pins 30 under lugs 31 formed on the ends of the end tray members 13. Rods 32 extend from the pivotally supported handles 14' and pass slidably through eye members 33 mounted upon the bottom of the tray extension plates 17'. With the tray end members 13 in their completely extended position as shown on the right hand side of Figs. 6 and 7, it is merely necessary to pivot the handles 14' to cause the rods 32 to be moved to urge the tray extension plates 17' downwards against the action of the springs which maintain them in a raised position. The tray extension members 17' are urged into a normal raised position by means of coil springs 18'.

This tray may be made of any suitable size, shape and material, such as metal, plastics, etc. It may be used as a carrying tray for food or other commodities.

In other respects this form of the invention is similar to that previously shown and like reference numerals identify like parts in each of the several views.

While I have illustrated and described the preferred embodiments of my invention, it is to be understood that I do not limit myself to the

precise constructions herein disclosed and the right is reserved to all changes and modifications coming within the scope of the invention as defined in the appended claims.

Having thus described my invention, what I claim as new and desire to secure by United States Letters Patent is:

1. A tray comprising a central member having a base wall and a pair of side walls extending upwards of said base wall, tray end members slidably mounted above said base wall and between said side walls, means for limiting sliding of said tray end members to extend from the ends of said central member, a tray extension plate vertically slidably mounted upon the base portion of said central member for moving up and between the edges of said tray end members when the latter are extended, and resilient means for urging said tray extension plate into its raised position, and means on said vertical side walls for limiting upward movement of said tray extension plate to a position in which the top face of said tray extension plate will be flush with the top faces of said tray end members.

2. A tray comprising a central member having a base wall and a pair of side walls extending upwards of said base wall, tray end members slidably mounted above said base wall and between said side walls, means for limiting sliding of said tray end members to extend from the ends of said central member, a tray extension plate vertically slidably mounted upon the base portion of said central member for moving up and between the edges of said tray end members when the latter are extended, and resilient means for urging said tray extension plate into its raised position, and means on said vertical side walls for limiting upward movement of said tray extension plate to a position in which the top face of said tray extension plate will be flush with the top faces of said tray end members.

3. A tray comprising a central member having a base wall and a pair of side walls extending upwards of said base wall, tray end members slidably mounted above said base wall and between

50 said side walls, means for limiting sliding of said tray end members to extend from the ends of said central member, a tray extension plate beneath each of said tray end members and each being vertically slidably mounted upon the base portion of said central member for moving up and between the edges of said tray end members when either or both of the latter are extended, and resilient means for urging said tray extension plates individually into their raised positions, handles pivotally mounted upon the outer ends of said tray end members, and rods extending from said handles and passing through eye members mounted on the bottoms of said tray extension plates for urging the plates downwards when the tops of the handles are pivoted inwards.

LORRAINE FARKAS.
